ABSTRACT OF THE DISCLOSURE

A fuel system having fluid logic components is provided with means of maintaining fluid back pressure within the fluid logic element at a constant level regardless of the attitude and operative situation of the fuel system. A preferred embodiment of the back pressure maintaining means comprises a narrow reservoir maintained behind a weir into which all fluid exhaust and vent passages are connected at an inlet point below the top of the weir. Fluid discharge in excess of the reservoir volume spills over the weir into a return line where it is returned to the fuel tank.

BACKGROUND OF THE INVENTION

Field of the invention

The present invention relates to the art of fuel handling and metering for mixture with air to provide a combustible mixture for an internal combustion engine. More specifically, the present invention relates to fuel systems which employ fluid logic elements to control the fuel metering.

Description of the prior art

A wide variety of fuel systems are well known in the art. Of recent appearance in the art are fuel systems which utilize fluidic devices to partially or totally control the fuel metering function. Examples of this art may be found in U.S. Letters Patent 3,386,710 issued to J. B. York, Jr., 3,389,894 issued to A. M. Binder and 3,406,951 issued to C. Marks to name a few. While the systems disclosed in the referenced patents utilize fluidic elements, they should not be thought of as complete systems since in an engine operating cycle these systems utilize an essentially constant fuel/air ratio whereas the fuel/air ratio must be varied to provide various enriched ratios such as cold start, acceleration, wide-open throttle, and full load enrichment. All of these variously ratioed enriched mixtures may be provided by controllably altering the control signals to the primary computing element through additional fluid logic circuitry. However, systems that provide accurate fuel/air ratios in tests simulating all engine requirements suddenly become highly inaccurate misapproximations when these identical systems are installed in automobiles wherein the system is subjected to vibration and other types of periodic and aperiodic motion.

It is a characteristic of all the known fluidic fuel systems that the main, or primary, fluidic stage comprises a nozzle discharging pressurized fluid into a fluid interaction region where control signals, disposed laterally of the fluid stream, deflect the stream towards one of a plurality of outlet ports. In systems where the fluid is fuel, one outlet port is associated with a fuel discharge nozzle in the air intake of the engine while another outlet port permits fuel entering thereinto to be returned to the fuel tank. In such systems when installed in vehicles, it has been found that accelerations and decelerations to which the vehicle is subjected are not instantaneously transmitted to the fuel thereby causing undesired variations in the

2

fuel pressure within the fuel system. This effect is not particularly noticeable on the fluid which is under positive pressure as at the fluid logic power nozzle. However, the effect is quite noticeable on the fuel in the return line which is unpressurized and in most instances must run the length of the automobile in the direction of greatest variations in acceleration. The vehicle descending of a grade or a deceleration of the vehicle caused by braking will cause the fuel in the return-line to tend to travel toward the return-line inlet. Since this is at the fluid interaction region of the fluid logic device or devices, this would cause a sudden increase in the pressure on that side of the power fluid stream thereby deflecting an undesirably high quantity of fuel into the outlet port associated with the air intake of the internal combustion engine causing the fuel/air ratio to be higher than that required for best engine performance.

On the other hand, vehicle acceleration would cause fuel in the return-line to flow away from the fluidic element at a higher flow rate than normal thereby causing a low pressure zone to form adjacent the power stream which would be operative to divert a larger portion of the power stream into the return line outlet passage of the fluidic element or elements. The fuel/air ratio would then become leaner than desired. It has, therefore, become evident that fluid logic fuel systems, at least as applied to automotive engines, require some means for maintaining the pressure in the fluid return outlet of the fluidic portion of the system at a substantially constant value which is unaffected by vehicle attitude or acceleration. It is a primary objective of this invention to provide, in an automotive fuel supply system, a means to maintain the fluidic portion fluid return port pressure at a substantially constant value regardless of vehicle attitude and acceleration. It is a still further object of the present invention to provide such a device which is reliable in operation and low in cost. It is a still further object of the present invention to provide a device for a fluidic fuel supply system capable of insulating the fluid logic metering portion of the system from the effects of acceleration and attitude upon the fuel in the fuel tank or return-line.

SUMMARY OF THE INVENTION

The present invention comprises the addition of a constant volume reservoir within the fuel return portion of a fluidic fuel system, in proximity to the fluidic computing and metering portion of the system which insulates that portion of the system from the fuel tank and from a major portion of the return-line. By discharging fuel directly into the center of this reservoir from the return-line port, and/or all vent ports of the fluidic elements, attitude effects upon the fuel return system are significantly reduced thereby stabilizing the attitude responsive component of the pressure variation at the fuel vent port in the primary metering element. Acceleration (inertial) effects are minimized by permitting only a minimum of fluid to be retained within the reservoir and by orienting the reservoir, with respect to the vehicle, so that an acceleration of the vehicle will cause minimal fluid forces to be exerted upstream of the reservoir.

BRIEF DESCRIPTION OF THE DRAWING

FIG. 1 shows, in schematic form, a fuel system for a vehicle incorporating the present invention.

FIG. 2 shows the preferred embodiment of the insulating reservoir means in a top view with the cover plate removed.

FIG. 3 shows the insulating reservoir means of FIG. 2 in a sectional view taken along line 3—3 in FIG. 2.

FIG. 4 shows a sectional view, taken along line 4—4 in FIG. 5, of an alternative isolating reservoir for use in the system shown in FIG. 1.

FIG. 5 shows a side view of the reservoir of FIG. 4.

DETAILED DESCRIPTION OF THE DRAWING

Referring now to the schematic diagram of FIG. 1, a representative fuel system is shown comprising a fuel tank 10, a fuel pumping means 12, a fuel metering and discharge means 14, and insulating means 16. Conduit 18 provides fuel to the pump inlet, conduit 20 communicates fuel under elevated pressure to the fuel metering and discharge means 14 and return conduit 22 communicates excess fuel from the insulating means 16 to the fuel tank 10. Return conduit 22 includes a check valve 24 which is operative to prevent fluid flow in the return line from reversing as might happen if the tank were elevated above the insulating means.

For completeness, the fuel metering and discharge means 14 has been illustrated as including a fluidic computation means illustrated as fluidic device 26 which includes a pair of outlet passages, 28 and 30, a pair of control passages 32 and 34 and a power stream input passage 36 which receives pressurized fuel from the fuel pump 12. Outlet passage 28 is adapted to receive the controlled power fluid stream from input passage 36 and to communicate the fluid, which in this instance is metered fuel, to a discharge nozzle 38 situated in the air intake 40 of an engine, not shown. The control passage 34 of the fluid logic amplifier 26 could be, for instance, in communication with the venturi 42 where it would receive as a control signal the depression at the venturi 42 which is indicative of air flow to the engine, not shown, and which would comprise the primary signal indicative of the engine fuel demand. Control passage 32 would be arranged to establish an operating bias for the amplifier 26 as, for instance, by connection to a pressure source such as the atmosphere. It will be recognized that while the fuel metering and discharge means 14 has only a single stage of amplification and receives but one control input, it is merely illustrative of a rudimentary fluidic fuel metering device of the type hereinbefore noted and of which more complete and complex forms are known. It should be evident that with more than one stage of amplification and additional fuel return or vent passages, the inertial effects upon the fuel in the return system become more critical.

Referring now to FIGS. 1, 2, and 3 and particularly to FIG. 3, the preferred embodiment of the present invention is illustrated. The insulating means 16 comprise an enclosure or body 100 having a partition or weir 102 situated therein to form a reservoir 103. The body 100 further includes a fluid inlet 104 arranged to discharge fluid into the reservoir 103 while a discharge passage 106 is arranged to exhaust fluid, in excess of the reservoir volume, from the enclosure 100. The discharge passage 106 is in communication with the return line 22 so that the fluid discharged, which in a fuel system as illustrated in FIG. 1 would be gasoline, would be returned to the fuel tank 10. The inlet to discharge passage 106 is shown as being sealed by floating ball 110. Other suitable means to prevent air from entering the return line would be applicable. An air inlet 108 is arranged to maintain the pressure within the enclosure at the prevailing atmospheric or an ambient pressure depending upon the pressure desired by the system designer.

The fluid inlet 104 communicates the reservoir 103 with the fluidic element vent passage means here illustrated by excess fluid outlet 30 but which should be considered representative of the fluid vents and excess fluid passages within the fluidic computing portion of the system. The fluid inlet is arranged to discharge all or substantially all, excess fluid into the reservoir. As will be observed, the reservoir has a pair of lateral dimensions and is oriented with the minor lateral dimension being parallel to the

direction of motion of the vehicle. This is indicated by the "MOTION" arrows in FIGS. 2 and 3.

Referring now to FIGS. 1, 4 and 5, and specifically to FIG. 4, an alternative embodiment of the insulating means 16 is illustrated. The insulating means 16 comprises a body 200 forming a chamber having a partition or weir 202 located therein forming a reservoir 203. The insulating means 16 further includes a fluid inlet passage 204 and fluid exhaust passage 206 located on opposite sides of the weir or dam 202. The outlet passage 206 is connected, via return line 22 including check valve 24, to the fuel tank 10. The fluid inlet passage 204 is located so as to discharge fluid substantially into the center of the reservoir 203 behind the weir 202 and is connected to the fuel vent and exhaust passage system of the fuel metering and discharge means 14. The fluid inlet 204 would be connected to each fuel return and vent passage in a fuel metering and discharge means 14 having more than one fluid logic element. The insulating device 16 is also of utility in those systems utilizing positive pressure, as opposed to the negative pressure venturi depression systems. The arrow labeled "MOTION" in FIG. 5 illustrates the orientation of the device with regard to the forward and reverse motion of a vehicle having forward and reverse motion parallel to the "MOTION" arrow.

OPERATION OF THE PREFERRED EMBODIMENT

In operation, fuel under pressure would be provided by pumping means 12 to the fluid logic element calculating stage 26 of the fuel metering and discharge means 14. Sufficient fuel would have to be provided so that there would be sufficient fuel available to satisfy the most extreme demands. This would mean that under all other operating conditions, the fuel provided to the main or primary metering element 26 would be in excess of the existing demand. The excess fuel would have to be returned to the fuel tank. The insulating device 16 is interposed between the fuel metering and discharge means 14, and fuel tank 10. The excess fuel is communicated through inlet passage 104 so as to fill the reservoir 103 to form a substantially constant volume reservoir of excess fuel. Fuel discharged in excess of the reservoir volume will spill over the partition or dam 102 where it will pass through the outlet passage 106 to return to the fuel tank 10. The insulating device 16 may be placed in proximity to the fuel metering and discharge means 14 so that the total volume of fuel within the conduit communicating the fluid logic element fluid vent to the reservoir is reduced. The insulating element 16 has a major lateral dimension which is substantially greater than the minor lateral dimension. This aids in reducing the volume of the reservoir. It is of particular advantage when the isolating device is oriented with the minor lateral dimension substantially parallel to the direction of vehicular motion, and hence the direction of the majority of acceleration forces. In this orientation, attitude changes to the fuel system are less pronounced and the narrowness of the reservoir causes fuel depth at the outlet of the fluid inlet passage 104 to remain substantially constant for vehicle acceleration and deceleration.

The depth of the reservoir 103 would be readily controllable by varying partition height or by varying the vertical placement of the passage 104 during fabrication of the isolating means 16 to provide a substantially constant back pressure on the fluidic computing and discharge means on the order of 1 to 2 inches of fuel. This substantially constant back pressure would permit the fuel system designers to virtually ignore the inertial force problems and to design the system to operate with a known, substantially constant back pressure.

By placing the outlet of the fluid inlet passage 104 at the approximate horizontal center of the reservoir 103, the changes in attitude of the vehicle will have slight effect on the static pressure head at the outlet. Further-

more, since the most pronounced attitude changes are experienced as a result of the vehicle negotiating a hill, the minor lateral dimension being parallel to such changes serves to further reduce the effect on the fuel return system.

It would also be possible to fabricate the fluid logic element or elements so that they could be located within the reservoir so that the length of line between the elements and isolating device reservoir may be further reduced.

I claim:

1. In a fuel system having a fluid element means to control fuel flow, the improvement comprising:

return means operative to divert excess fluid to the fluid supply; and isolating means interposed in the return means downstream of the fluid element means operative to substantially eliminate the influence of the inertial effects of the fluid in the return means on the fluid element means.

2. The system as claimed in claim 1 wherein said isolating means comprise:

means for forming a reservoir in substantially constant pressure communication with the fluid return passage of the fluid logic device; and means for returning fluid in excess of the reservoir volume to the fluid supply.

3. The system as claimed in claim 1 wherein said isolating means comprise:

a chambered body having a fluid inlet means and a fluid exhaust means; said fluid inlet means communicating with the fluid return passage of the fluid logic device via a first portion of the return means; said fluid exhaust means communicating with the fluid supply via a second portion of the return means; a partition located in said chambered body operative to form a reservoir region in the vicinity of said fluid inlet means; and said reservoir operative to prevent direct fluid communication between said fluid inlet means and said fluid exhaust means.

4. The system as claimed in claim 3 wherein said reservoir has a pair of lateral dimensions and said fluid inlet means includes an inlet port substantially at the middle of said pair of lateral dimensions.

5. The system as claimed in claim 4 wherein one of said lateral dimensions is substantially larger than said width dimension.

6. The system as claimed in claim 5 wherein the minor lateral dimension is oriented to be substantially parallel to the direction of the majority of inertia forces exerted on the system.

7. The system as claimed in claim 4 wherein said inlet port is in a plane substantially parallel to the direction of the majority of inertia forces exerted on the system.

8. The system as claimed in claim 3 wherein said fluid inlet means includes a fluid inlet port arranged to discharge fluid into said reservoir thereby establishing a substantially constant fluid back pressure for the fluid logic device metering means.

9. The system as claimed in claim 8 wherein said inlet port is arranged to be substantially parallel to the direction of the majority of inertia forces exerted on the system.

10. A fuel system for engines comprising:

a source of fluid; pumping means communicating with said source of fluid operative to provide a pressurized fluid stream; fluidic means for receiving said fluid stream and operative to produce a first fluid flow controlling engine fuel;

return means for returning the portion of said fluid stream in excess of said first fluid flow to the source of fluid; and

including insulating means operative to maintain a substantially constant level of fluid pressure in said return means between said fluidic means and insulating means.

11. In a fuel system having a fluidic amplifier means to control fuel flow, the improvement comprising:

return means having a fluid inlet at the fluidic amplifier means operative to divert excess fluid away from the fluidic amplifier means; and

means operatively associated with the return means to provide a substantially constant fluid pressure at the return means fluid inlet.
